UNITED STATES PATENT OFFICE.

BOYCE W. REYNOLDS, OF MORGANTOWN, WEST VIRGINIA.

GARBAGE RECEPTACLE.

Application filed October 19, 1923. Serial No. 669,601.

This invention is a receptacle of the type designed for temporary storage of garbage and other similar refuse.

One of the objects of the invention is to provide a sanitary storage receptacle of temporary character which may be replaced at any time by a new one, thereby eliminating the necessity of cleansing receptacles of this type. A further object is to provide a garbage receptacle embodying a supporting means and a flexible sanitary receiving sack which may be removed when filled and a new one substituted, and engaged with the supporting means. A further object is to provide means for maintaining the mouth of the sack in close contact with the walls of a supporting member in such manner as to prevent the refuse from passing between the supporting member and the mouth of the sack.

The invention will be hereinafter fully set forth and particularly pointed out in the claims.

In the accompanying drawings:

Fig. 1 is a vertical sectional view of one embodiment of the invention.

Fig. 2 is an enlarged fragmentary sectional view of the same.

Fig. 3 is a top plan view of the invention.

Figs. 4 and 5 are detail elevations of locking rings embodied in the invention.

Figs. 6 and 7 are detail perspectives of other modified embodiments of the locking rings.

Fig. 8 is an elevation of a modified form of removable receptacle used in conjunction with the invention.

Fig. 9 is a vertical sectional view of the same.

Fig. 10 is a top plan view.

Fig. 11 is a fragmentary horizontal sectional view taken on line 11—11 of Fig. 8.

Fig. 12 is a diagrammatical view showing several of the removable containers in nested relation.

Referring to Figures 1, 2 and 3 of the drawing, 12 designates a cylindrical casing which may be constructed of any suitable material such as metal, rubberoid or any other moisture-proof material possessing the desired durability. Secured to the lower end of said casing 12 by suitable means such as rivets 14 is a circular channel shaped

reinforcing band 13. The casing 12 is supported by a removable base 17 having a central off-set portion 16, which projects into the casing and forms a bottom therefor. Said base has a down turned supporting flange 18 upon which it rests.

Secured to the reinforced band 13 by means of the transverse rivets 14 are L-shaped latch elements 19, the lateral legs of which rest upon the base 17 and are engageable with keepers 20 fixed to this base at spaced intervals. Each of these keepers 20 includes a strip of metal bent to approximately Z-shape and having one end secured to the base as at 21, while its opposite end is spaced from the base and slidably receives the lateral legs of the latch element 70 therebetween.

A reinforcing band 22 substantially similar to the band 13 is secured to the upper end of the casing 12, and is provided with an internal annular bead or rib 23 which is disposed within the casing 12.

Arranged within the casing 12 is a removable container designated in its entirety at 26 and received in the upper end of this container is a resilient band 25, the latter holding the mouth of the receptacle against the beading or rib 23.

In Figs. 8 to 12 inclusive, are illustrated a modification of the container used in conjunction with Fig. 4. This container comprises a flexible and slightly tapered water-proof tube 26, which is constructed from any desirable material possessing the tensile strength and is treated with suitable moisture-proof material such as paraffin. Located within the lower end of the flexible tube 26 is a relatively rigid bottom 27 preferably constructed of card-board or other stout material and coated with paraffin or other moisture-proof material. This bottom 27 is formed with a corrugated annular flange 28, which is secured to the lower end of the flexible tube by gluing or other desirable manner.

Fig. 11 shows a manner of connecting these two parts together and it will be observed that the corrugated surfaces will provide a relatively strong bond between the parts. The type of locking ring shown in Fig. 4 includes an expansible band or ribbon 29 having its ends arranged in overlapping rela-

tion and riveted or otherwise secured together as at 30. In this instance, the band will be squeezed together to insert the same within the mouth of the removable receptacle and in placing this band in position it is gradually released to permit itself to conform to the side walls of the casing.

In Fig. 5 a split band 30 is provided and in assembling this band with the device the ends thereof are arranged in overlapping relation and upon releasing the same the band will expand and the ends thereof will abut as shown in Fig. 5.

In Fig. 6 the band is substantially C-shaped in cross section and one end carries a longitudinal tongue 31, which is slidably received in the adjacent end of the band.

In Fig. 7 a lever 32 is hinged to one end of the band and carried by this lever; adjacent its hinged end is a plate 33 provided with a transverse shoulder 34. The opposite end of the band is provided with angularly disposed inturned flange 35, which contacts with the plate and engages the shoulder. In this form of the band the resiliency alone is not depended upon to lock the same in position as the parts are forced into engagement with the mouth of the receptacle and casing by the cam action of the lever 32.

The usual covering 36 having a handle 37 is received upon the upper end of the casing.

In practice the house-wife will be provided with any desired number of duplicate moisture-proof sacks which will be retained on hand for use as may be required. After a sack which has previously been inserted and secured within the receptacle 12, has been filled with garbage or other refuse, said sack may be removed and disposed of in any desired manner and a new one substituted therefor. In this manner the refuse is disposed of in a sanitary manner and cleansing of garbage receptacles is rendered unnecessary.

Having thus explained the nature of the invention and described an operative manner of constructing and using the same, although without attempting to set forth all of the forms in which it may be made, or all of the forms of its use, what is claimed is:—

1. A refuse receptacle of the character described comprising a casing open at its top, a split band engaging the inner surface of said casing contiguous to said open top, and a sack having its open mouth normally clamped between said split band and said casing, and means cooperating with said band to distort the shape of the contiguous portion of the sack.

2. A refuse receptacle of the character described comprising a casing open at its top and provided with an internal bead spaced from its top edge, a split band engaging the inner surface of said casing above said bead,

and a sack having its open mouth normally clamped between said split band and the casing so that the contiguous portion of the sack will be distorted by said bead.

3. A refuse receptacle of the character described comprising a casing open at its top, a channel shaped reenforcing band engaging the top edge of said casing and provided with a bead positioned within the casing, a split band engaging the inner surface of said reenforcing band above said bead, and a sack having its open mouth normally clamped between the reenforcing band and said bead so that the contiguous portion of the sack will be distorted by said bead.

4. A refuse receptacle of the character described comprising a casing open at its top, a removable bottom therefor, the diameter of said bottom being greater than the diameter of said casing so as to provide a flange extending outside of the casing, means for detachably connecting the casing to the flange-like extension of said bottom, a container removably located within said casing, and means for clamping the mouth of the container to the mouth of the casing.

5. A refuse receptacle of the character described comprising a casing open at its top, a removable bottom therefor, the diameter of said bottom being greater than the diameter of said casing so as to provide a flange extending outside of the casing, means for detachably connecting the casing to the flange-like extension of said bottom, a container removably located within said casing, and a resilient band normally located within the mouth of the container to hold the same in contact with the walls of the casing, the upper end of said container being disposed below the upper edge of the band so as to prevent refuse from entering the space between the receptacle and the upper edge of the container.

6. A refuse receptacle of the character described comprising a casing, channel shaped reenforcing elements upon the end of the casing, a bottom removably secured to said casing and having a central portion projecting into the contiguous end of the casing, a sanitary container removably located within the casing and having its bottom resting upon the projecting portion of the casing bottom, and means for holding the mouth of the container in contact with the casing.

7. A refuse receptacle of the character described comprising a tubular casing, a removable bottom therefor, said bottom being of a greater diameter than the diameter of the casing so as to provide an annular flange extending from said casing when the members are engaged, keepers carried by the top surface of said flange-like portion, and L-shaped latch elements of flat cross-section carried by the casing and positioned to engage said keepers.

8. A receptacle of the character described comprising a casing open at its top and its bottom and provided with an internal bead spaced from its top edge, a removable bottom, means for removably retaining said removable bottom in place, a split band engaging the inner surface of said casing above

10
said bead, and a sack having its open mouth normally clamped between said split band and the casing so that the contiguous portion of the sack will be distorted by said bead.

In testimony whereof I affix my signature.
BOYCE W. REYNOLDS.
